CLAIM

The ornamental design for a lighting signature, as shown and described.

DESCRIPTION

The patent or application file contains at least one drawing executed in color. Copies of this patent or patent application publication with color drawings will be provided by the Office upon request and payment of the necessary fee.

FIG. 1 is a front perspective view of a vehicle component lighting signature in color;

FIG. 2 is a side view of a vehicle component lighting signature in color;

FIG. 3 is a front view of a vehicle component lighting signature in color;

FIG. 4 is a front perspective view of a vehicle component lighting signature in black and white;

FIG. 5 is a side view of a vehicle component lighting signature in black and white; and,

FIG. 6 is a front view of a vehicle component lighting signature in black and white.

The diagonal lines shown on the drawings depict portions of the vehicle component that form no part of the claimed design.
